UNITED STATES PATENT OFFICE

CHARLES SHIELDS McINTIRE, OF LONDON, ENGLAND, ASSIGNOR TO MAC CHANGERS
(1929) LIMITED, OF LUTON, ENGLAND, A COMPANY OF GREAT BRITAIN

ADVERTISING DEVICE

Application filed April 20, 1929, Serial No. 356,664, and in Great Britain May 15, 1928.

This invention relates to advertising devices and has for its object to provide an improved construction of device adapted for use in conjunction with machines and apparatus such as cash registers, money changing machines and the like.

In accordance with the invention there are provided in the upper part of the casing of the apparatus or machine behind a glazed opening at each side thereof sprocket wheels on which are suspended chains. Between the links of the chains are secured plates or the like containing suitable advertising matter which plates are adapted to be brought in succession on each partial rotation of the sprockets opposite the glazed opening. These sprockets are turned through part of a revolution to bring another plate opposite the glazed opening, on each operation of one of the press levers of the machine by gearing operated by clockwork or by the press lever or the like. Thus on each depression of one of the press levers or the like the sprockets are partially rotated and a new advertisement is projected in front of the glazed opening.

A lamp may be located in the back of the casing behind or beneath the advertising device so as to illuminate the plates containing the advertisements. Soft illumination of these plates may be obtained by providing between the source of light and the plates an opal or other shade.

The invention will be more fully understood from the following description in connection with the annexed drawings in which the invention is illustrated as applied to a note changer casing having two press levers, the note changer mechanism not being shown as it forms no part of the present invention which as before stated, may be used with other classes of machines.

Figure 1 is a back view of a casing showing the mechanism forming the invention with the back of the casing removed.

Figure 2 is a side sectional elevation of a complete casing and showing the mechanism.

Figure 3 is an elevation of a device for holding the belt when a plate is in position to prevent slipping.

According to this invention positioned in

suitable bearings actuated on each side of the casing are two shafts 4, 5 arranged on above the other and each of these shafts 4, 5 carries two sprocket wheels 6, 6, 7, 7 positioned at a distance apart according to the width of the advertising medium.

These sprocket wheels 6, 6, 7, 7 are preferably constructed as discs provided with recesses 6^a, 7^a on their edges.

The advertising devices consist of a number of plates or frames 8 containing plates 9 of glass or other material and these frames are connected by links 10, the pivotal points of the links 10 at the side edges of the frame 8 being at a distance from the corners of the frame and the pivot pins extend to outside the chain of advertising devices to form pivot pins 11 which have a bearing in the recesses 6^a, 7^a of the sprocket wheels 6, 6, 7, 7 as they are rotated.

The chain of frames 8 and links 10 is endless and is carried by the sprocket wheels, the main body of the chain of frames being vertical.

The lower two sprocket wheels 6, 6 are provided on their outer faces with four projecting pins 12 which pins are successively acted upon each by a hooked pawl 13 pivoted to one arm of a bell crank lever 14 pivoted at 14^a to the casing 15 or a fixed bearing. The pawl 13 is provided between its ends with an arm 16 controlled by a spring 17 secured at one end to the casing 15 and the other to the arm 16.

The other end of the bell crank lever 14 is connected to one end of a link 18 pivoted at 19 to a sliding rod 20 controlled by a spring 21. The sliding rod 20 also carries by an arm 20^a, another link 22 pivoted at 23, the other end of the link being connected to one arm of a bell crank lever 24 pivoted at 25 to the casing, the other arm of the bell crank lever being pivoted to a link 26 connecting a press lever 27 pivoted at 28 to the casing 15.

There is one set of each of the pawls and mechanism connecting a press lever on each side of the chain of advertising matter.

Inside the chain and suspended from the shaft 5 is a lamp casing 29 carrying electric lamps 30 connected up with a switch and source of supply for illuminating the adver-

tisements from the back as they are exposed, and a sheet 31 of translucent glass may be fitted to the casing 29 to diffuse or soften the light.

It is preferred to provide a device for holding the sprocket wheels in each placed position without fear of slip after each action and for this purpose a bar 32 is secured to one side of the casing (in the drawings a strip 33 is shown provided with bearings for carrying the shafts 4, 5, such strip being secured to the sides of the casing) or to the strip 33 on one side only and from the ends of this bar depend two arms 34, 34 connected together at their lower end by a spring 35 and in this case the sprocket 7 next to such a device is provided with four pins 36 spaced in equal relation with the pins 12 on the sprocket 6 so that as the sprockets are revolved the pins 36 spread the lower ends of the arms 34, 34 and when they have passed over the centre line the spring 35 will draw the arms 34, 34 together and the arms 34 will then each bear against a pair of pins and hold 25 the sprockets against rotation but ready for the next action.

In the upper part of the front of the casing is a glazed opening 37 immediately in front of one of the frames or plates 8, 9 containing 30 the advertisements which is illuminated by the lamps 30.

Either lever 27 can operate the chain of advertisements separately and in doing so one pin 12 will leave the pawl 13 and acting 35 against same will push it away against the resistance of the spring 17 and the next pin 12 will ride over the nose of the pawl 13 until it passes below the hook portion of the pawl, whereupon the spring 17 will cause the 40 hook portion of the pawl to engage such pin 12 for the next operation.

The action is as follows:

On depressing the lever 27 the link 26 and bell crank lever 24, link 22, sliding rod 20 45 and link 18 will actuate the bell crank 14 and pull down the pawl 13, the notch of which will act on the pin 12 then seated in the notch and partially rotate the sprocket 6 and thus move the endless chain of advertisements and also partially rotate the sprockets 50 7 for the full movement of the pawl 13 during which movement the glass 9 and frame 8 behind the glazed opening 37 will be moved to be on the top of the sprockets 7, see Figure 2, and the following glass 9 and frame 8 will be exhibited behind the glazed opening. During this movement the springs 17 and 21 55 have been put in tension.

On a release of the lever 27 the spring 21 60 will return the lever 27 and its connections and also the bell crank 14 and pawl 13 and assisted by the spring 17 which at the same time positions the pawl for its notch to engage the next pin 12 which during the move- 65

ment has been riding over the nose of the pawl 13.

The same action occurs on the operation of either lever 27 the pins 12 sliding over the nose of the pawl of the nonoperated lever as 70 before explained.

By connecting the links 10 to the frames 8 at a distance from the corners, the frames engage the recesses 6^a, 7^a in the sprockets 6, 7, the frames are kept flat for exhibiting 75 and during movement of the chain.

What I do claim as my invention and desire to obtain by Letters Patent is:—

An advertising device comprising a casing having a glazed opening, two pairs of sprocket wheels each carried by a shaft positioned at a distance apart, an endless chain comprising members carrying advertisements, links pivoted to the members by pivot elements at a distance from the corner on each side edge, the pivot elements also being adapted for engagement with the sprocket wheels, the endless chain being carried between the sprocket wheels, pins projecting outwardly from two of the sprocket wheels, a spring controlled notched pawl for engaging the pins on each sprocket wheel, bell crank levers pivoted to the casing and pivotally carrying the pawls, and a spring controlled rod pivotally connecting the bell 80 crank lever with operating mechanism.

In testimony whereof I have hereunto set my hand.

CHARLES SHIELDS McINTIRE.
